UNITED STATES PATENT OFFICE.

EDWIN A. JONES, OF ST. LOUIS, MISSOURI.

HEATING SYSTEM.

Application filed May 21, 1920. Serial No. 383,153.

To all whom it may concern:

Be it known that I, EDWIN A. JONES, a citizen of the United States, residing at St. Louis, Missouri, have invented a certain new 5 and useful Improvement in Heating Systems, of which the following is a full, clear, and exact description, such as will enable others skilled in the art to which it appertains to make and use the same.

10 This invention relates to steam and hot water heating systems.

One object of my invention is to provide a steam or hot water heating system of novel construction in which it is possible to maintain 15 a vacuum in the radiators or other heat radiating devices of the system with pressure on the supply lines leading to the radiators, thereby permitting the transmission of a greater portion of the heat units in the heating medium to the air surrounding the radiators than is possible with the steam and hot water heating systems now in general use.

Another object is to provide a heating 20 system which insures a high degree of efficiency of the radiators or heat radiating devices of the system under all conditions of piping installation without the use of packed valves.

To this end I have devised a heating system 25 wherein the supply of the heating medium to a radiator or heat radiating device of the system is regulated by a governing device of novel construction controlled by the exhaust or discharge of the heating medium from said radiator or heat radiating device. Briefly described, my improved system comprises radiators, coils or other suitable heat radiating devices, a supply line and a return line combined with each radiator, a 30 packless valve in the supply line of each radiator for governing the admission of the heating medium to the radiator and a device arranged in close proximity to said valve and adapted to be operated or rendered 35 operative by the escape of the heating medium from said radiator for positively actuating the movable part of said valve that governs the admission of the heating medium to the radiator.

40 Figure 1 of the drawings is a vertical sectional view, illustrating one type of valve and automatic regulating device that can be used in my improved heating system for automatically controlling the admission of the heating medium to a radiator or heat radiating device of the system; and

Figures 2, 3 and 4 are diagrammatic views, illustrating various ways of connecting the supply and return lines with the radiators of the system.

45 My invention is applicable to both steam and hot water heating systems, and therefore, I have used the term "heating medium" to include both steam and hot water. In Figure 2 of the drawings I have illustrated a heating system constructed in accordance with my invention, wherein each radiator or heat radiating device A of the system is provided with a supply line 1 that is connected to one end of the radiator at the bottom of the radiator and a return line 2 that leads from the bottom of the opposite end of the radiator.

50 Figure 3 illustrates a system wherein the supply line 1 of each radiator is connected to one end of the radiator at the top of the radiator, and the return line 2 leads from the same end of the radiator at the bottom of the radiator.

55 Figure 4 illustrates a system wherein the supply line 1 of each radiator is connected to one end of the radiator at the top of the radiator and the return line 2 leads from the opposite end of the radiator at the bottom of the radiator. Each radiator of the system is provided with a manually-operable valve 3 for controlling the supply of the heating medium to the radiator.

60 Each radiator of the system is provided with a packless valve arranged in the supply line 1 leading to the radiator and equipped with a movable member B that governs the supply of the heating medium to the radiator. A device C adapted to be operated or rendered operative by the escape of the heating medium through the return line 2 leading from the radiator is arranged in close proximity to said valve for positively actuating the movable element B of the valve so as to automatically diminish or cut off the supply of the heating medium to the radiator. Various types or kinds of packless valves can be used and various types or kinds of devices can be used for actuating the movable controlling elements of said valves. Therefore, I do not wish it to be understood that my invention is limited to a system provided with valves B of the kind herein shown, or valve actuating devices of the kind herein shown.

65 70 75 80 85 90 95 100 105 110 In Figure 1 I have illustrated one type of valve and valve actuating device that can

- be used in my improved system, the valve comprising a casing 4 arranged in the supply line 1 of the radiator with which the valve is associated and provided with a partition 5 having a port 6 therein that is surrounded by a seat on which the movable element B of the valve presses, so as to cut off the supply of the heating medium to the radiator. The device that is used to positively 10 actuate the movable element of the valve is arranged in close proximity to the valve and consists of a thermostat provided with a diaphragm C and a bulb 8 that contains a volatile substance, which, upon being subjected 15 to heat, expands and thus causes the diaphragm C to move in such a direction that it seats the movable element B of the valve or moves it positively towards its seat so as to diminish the supply of the heating medium to the radiator, the movement of the 20 diaphragm being imparted to the movable element B of the valve by means of a pusher 7^a which is arranged in alignment with the steam 7 of said valve. The bulb 8 is arranged in the return line 2 leading from the 25 radiator so as to cause the position or condition of the element B of the valve to be governed automatically by the escape of the heating medium from the radiator.
- 30 In a steam heating system constructed in accordance with my invention, when the steam in a radiator A of the system is in excess of the condensing power of the radiator, the surplus steam which escapes or 35 discharges from the radiator through the return line 2 will act on the bulb 8 of the thermostat and thus cause the diaphragm C to move in such a direction as to close or partially close the movable element B of the 40 inlet valve of said radiator, thereby cutting off or diminishing the supply of steam to the radiator. In a hot water system constructed in accordance with my invention, the water which escapes from a radiator of 45 the system through the return line 2 leading from the radiator will act on the bulb 8 of the thermostat when said water is above a predetermined temperature, and thus cause the inlet valve to be closed or partially 50 closed by the movement of the diaphragm C.
- In a heating system of the construction above described it is possible to maintain a vacuum in the radiators or heat radiating devices of the system with pressure on the supply lines leading to the radiators, thereby 55 permitting the transmission of a greater portion of the heat units in the heating medium to the air surrounding the radiators than is possible with any of the various types of 60 steam and hot water heating systems now in general use. Such a system permits the use of an open return system of piping without the use of return traps or packed valves, and moreover, it enables the highest efficiency of the radiators to be attained under

all conditions of piping installations. In my improved system the air surrounding a radiator or heat radiating device of the system will be maintained at a more even temperature than is possible with the heating systems now in use, for the reason that my system insures each radiator being supplied with just the quantity of heating medium that the radiator will use or condense, any surplus or excess supply of heating medium causing the inlet valve of the radiator to close automatically. My claim for maintaining the surrounding air at an even temperature is based on the fact that as the air surrounding a radiator increases in temperature, the radiator decreases its condensation, causing an excess or surplus of steam, the discharge of which from the radiator causes the movable element B of the inlet valve of the radiator to close automatically 70 the supply line 1 leading to the radiator. When the air decreases in temperature the condensing capacity of the radiator is increased, causing transmission of more heat, which, in turn, raises the temperature of the 75 surrounding air.

In order to eliminate the possibility of the diaphragm C being affected by the heating medium which is supplied to the radiator through the supply line 1, I prefer to arrange an air chamber D between the diaphragm C and the casing 4 of the valve B, said chamber D being provided with air inlet holes 9, as shown in Figure 1. In order to overcome the necessity of using a packed joint at the point where the stem 7 of the valve projects through the casing 4 of the valve, I prefer to arrange a diaphragm E outside of the casing 4 of the valve in substantially parallel relation to the wall of 80 said casing through which the stem 7 of said valve passes, the peripheral edge portion of said diaphragm E being clamped between the outer wall of the air chamber D and a gasket 10 that bears against the valve casing 4, as shown in Figure 1. The diaphragm E bears against the stem 7 of the movable element B of the valve and the pusher 7^a is interposed between the diaphragms E and C. The thermostat as an 85 entirety is clamped between the outer wall of the air chamber D and a housing 11 that receives the bulb 8 and which forms part of the return line 2, a gasket 12 being arranged 90 between said housing 11 and the peripheral edge portion of the thermostat so as to produce a tight joint between said parts. The member that forms the outer wall of the air chamber D is provided with a spider 9^a in which the pusher 7^a is guided. In the 95 thermostat valve shown in Figure 1 the casing 4 that forms part of the supply line, the housing 11 which forms part of the return line, and the ring-shaped member interposed between said parts that forms the 100

outer wall of the air chamber D, are clamped together by bolts 13, as shown in dotted lines in Figure 1; but it will, of course, be obvious that the inlet valves of the system and the controlling devices that are associated with same can be constructed in various ways without departing from the spirit of my invention.

Having thus described my invention, what I claim as new and desire to secure by Letters Patent, is:

- 5 1. A heating system, comprising heat radiating elements, each of which is provided with an inlet and an outlet, a packless valve associated with the inlet of each heat radiating element, a heat operated governing device associated with the outlet of each heat radiating element and combined with said valve in such a way as to form a unitary 15 structure, means actuated by said governing device for positively actuating the movable part of the valve that controls the supply of the heating medium to the heating element, and means for preventing said heat operated governing element from being affected by the heat of the heating medium supplied to the heat radiating element through said inlet.
- 20 2. A heating system, comprising heat radiating elements, a supply line and a return line associated with each of said heat radiating elements, a packless valve in the supply line of each heat radiating element, a governing device in the return line of each heat radiating element operated by the heat of the heating medium and arranged in close proximity to said valve for positively actuating the movable part of said valve that 25 controls the admission of the heating medium to the heat radiating element, and an air chamber arranged between said govern-

ing device and the casing of said valve for the purpose described, said valve casing, air chamber, and governing device being combined into a single structure.

3. A heating system, comprising heat radiating devices, a supply line and a return line associated with each of said heat radiating devices, a packless valve in the supply line of each heat radiating device provided with a movable element and equipped with a casing having a flexible wall to which said movable element is connected, a heat operated means arranged in the return line of each heat radiating device in proximity to the flexible wall of said valve for positively actuating the movable element of the valve so as to regulate the supply of the heating medium to the heat radiating device and an air circulating chamber arranged between said flexible wall and said heat operated means, for the purpose described.

4. A heating system comprising heat radiating devices, each of which is equipped with a supply line and a return line, a packless valve in the supply line of each heat radiating device provided with a movable controlling element and comprising a casing equipped with a flexible wall to which said movable element is secured, a thermostat arranged in the return line of each heat radiating device in proximity to the valve in the supply line of said device, means interposed between said flexible wall and said thermostat for automatically changing the position of the movable element of said valve, and means for preventing said thermostat from being affected by the heat of the heating medium flowing through said supply line.

EDWIN A. JONES.
